(57) **CLAIM**

The ornamental design for a handle for wire stripper, as shown and described.

DESCRIPTION

FIG. 1 is a front, right and top side perspective view of a handle for wire stripper showing our new design;
FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the handle for wire stripper that form no part of the claimed design.
